UNITED STATES PATENT OFFICE.

ERNEST S. ROE, OF PLYMOUTH, MICHIGAN, ASSIGNOR TO MARKHAM AIR RIFLE COMPANY, OF PLYMOUTH, MICHIGAN, A CORPORATION OF MICHIGAN.

AIR GUN.

Application filed February 6, 1923. Serial No. 617,317.

To all whom it may concern:

Be it known that I, ERNEST S. ROE, a citizen of the United States of America, residing at Plymouth, in the county of Wayne 5 and State of Michigan, have invented certain new and useful Improvements in Air Guns, of which the following is a specification, reference being had therein to the accompanying drawings.

10 The invention relates to guns and refers more particularly to air guns or rifles. One of the objects of the invention is to provide a gun with means for locking the discharging mechanism from accidental movement 15 when the trigger is in cocked position, this locking means being dependent for its release upon movement of the trigger. Another object is the provision of a gun in which the trigger itself is automatically 20 locked when in cocked position whereby the plunger of the discharging mechanism is locked from accidental movement. Further objects of the invention reside in the novel features of construction and combinations 25 and arrangements of parts as more fully hereinafter set forth.

In the drawings:

Figure 1 is a side elevation of an air gun embodying my invention;

30 Figures 2 and 3 are longitudinal sectional elevations of a portion thereof showing the parts in different positions;

Figure 4 is a perspective view partly broken away of the trigger mechanism;

35 Figure 5 is a section through the trigger mechanism.

1 is the stock of the air gun and 2 the barrel section thereof. The stock has at its forward end the casing 3 which forms the 40 housing for the discharge mechanism including the air compression chamber 4, the plunger 5 and the coil spring 6 for actuating the plunger in one direction. The trigger mechanism 7 is also housed within 45 the casing. 8 is a stationary abutment secured in the forward end of the air compression chamber 4 and having the axial opening 9 therein for the passage of the air.

The barrel section is pivoted to the forward end of the casing at 10 and the break down movement of this barrel section about its pivot is utilized for compressing the coil spring and cocking the air gun. The barrel section has the depending side flanges 11 at 55 its rear end and the casing has the depend-

ing side flanges 12, the adjacent ends of which are pivotally connected together at 10. The rod 13 which is preferably U-shaped is pivotally connected at its ends to the depending side flanges 11 and its base 14 extends through the parallel longitudinally extending slots 15 in the depending side flanges 12 and is adapted to engage the down-turned end 16 of the shank secured to the plunger 5, the arrangement being such that the plunger is longitudinally moved backward to compress the coil spring upon the breaking-down movement of the barrel section. The trigger mechanism 7 is also moved upon the breaking-down movement 70 of the barrel section to cocked position, at which time it engages the downturned end 16 of the plunger shank to retain the latter in its rearwardly adjusted position.

For the purpose of locking the discharge mechanism from movement when the gun has been cocked, I form the trigger mechanism 7 of the inner member 17 and the outer member or trigger 18 which are pivoted at 19 between the depending side flanges 12 80 of the casing 3, these members having at their forward ends the upwardly extending latches 20 and 21 respectively which are engageable with the downturned end 16 of the plunger shank. The outer member or trigger 18 is preferably formed of a sheet metal stamping and has the side walls 22 on opposite sides of the inner member 17 and the downwardly extending finger portion 23 have a rounded front face. The side walls 90 are formed with shoulders forming the latch 21. To permit of movement of the outer member or trigger 18 longitudinally of the casing and relative to the inner member 17, its side walls are formed with the elongated 95 openings 24 which are slidably engaged in by the pivot 19 of the trigger mechanism. The inner member 17 has a fixed axis of movement about this pivot and is rocked from the outer member or trigger 18 by the pin 25 extending between the side walls of the outer member or trigger and slidably engaging in the longitudinally extending elongated opening 26 in the forward end of the inner member. With this arrangement 100 the outer member or trigger can rock the inner member about its pivot and can be moved longitudinally relative to the inner member. The outer member or trigger has the notch 27 in its front face which is adapt- 110

ed to be engaged in by the transverse flanges 28 at the lower ends of the side flanges 12 of the casing when the gun has been cocked and the trigger moved to cocked position, this latter movement being accomplished by means of the depending end 16 of the plunger shank engaging the rear upwardly extending shoulders 29 formed upon the side walls of the outer member or trigger. After the trigger mechanism has been moved to cocked position, the notch in the front face of the outer member or trigger is in registration with the transverse flanges of the casing side flanges and the outer member or trigger is automatically moved longitudinally of the casing to bring these transverse flanges into engagement in the notch by means of the coil spring 30 secured between the rear ends of the side walls of the outer member or trigger and the forward end of the stock 1.

In operation, the barrel section 2 is broken down and the plunger 5 moved rearwardly and the trigger 23 moved to cocked position by means of the rod 13 pivotally connected to the barrel section and engaging the depending end 16 of the plunger shank. The parts are then in the position shown in Figure 2 with the notch 27 in the outer member or trigger 18 of the trigger mechanism in alignment with the transverse flanges 28 upon the casing. Upon returning the barrel section to its shooting position, the depending end 16 of the plunger shank is allowed to move slightly forward to engage the latch 20 of the inner member 17 of the trigger mechanism. This permits the coil spring 30 to force the outer member or trigger 18 forwardly to bring the transverse flanges of the casing into engagement in the notch in the front face of the outer member or trigger. The discharge mechanism of the gun is now locked from accidental disengagement. To release the outer member or trigger and permit of the rocking of the trigger mechanism about its pivot, the trigger is first pulled back longitudinally of the casing to release the shoulder forming the upper edge of the notch in the outer member or trigger from the casing transverse flanges. Continued rearward movement of the outer member or trigger then compels rocking of both the outer member or trigger and the inner member about the pivot of the trigger mechanism which releases the depending end of the plunger shank from the latches formed upon both the outer member or trigger and the inner member.

From the above description it will be readily seen that I have provided an air gun of simple construction in which the discharge mechanism is locked from accidental disengagement from the trigger mechanism and in which the locking means is depend-

ent for its release upon movement of the trigger.

What I claim as my invention is:

1. In a gun, the combination with discharging mechanism, of a trigger for controlling said discharging mechanism movable to cocked position, means for holding said discharging mechanism from discharge when said trigger is in cocked position, and means for locking said discharging mechanism from accidental discharge when said trigger is in cocked position, said locking means being dependent for its release upon movement of said trigger. 70

2. In a gun, the combination with discharging mechanism including a plunger, of a trigger for controlling said plunger movable to cocked position, means for holding said plunger from discharge when said trigger is in cocked position, and means for locking said plunger from accidental movement dependent for its release upon disengagement of said trigger. 80

3. In a gun, the combination with discharging mechanism, of a trigger for controlling said discharging mechanism movable to cocked position, and means for locking said trigger in cocked position against accidental rotary movement, said locking means being dependent for its release upon the substantially linear movement of said trigger. 90

4. In a gun, the combination with discharging mechanism including a plunger, of a trigger for controlling said plunger movable to cocked position, and means for locking said trigger in cocked position against accidental rotary movement, said locking means being dependent for its release upon linear movement of said trigger. 100

5. In a gun, the combination with discharging mechanism, of a trigger having a rotary and a linear movement for controlling said discharging mechanism, means for moving the trigger to cocked position, and means separate from said trigger cocking means for automatically locking the trigger in cocked position, against accidental rotary movement. 110

6. In a gun, the combination with discharging mechanism including a plunger, of a trigger for controlling said plunger, means for cocking the gun and moving said trigger to cocked position, means for holding said plunger from discharge and means for locking said trigger in cocked position from rotary movement, said trigger releasing said locking means during a portion of its movement in one direction, and releasing said plunger during a subsequent portion of its movement in the same direction. 115

7. In a gun, the combination with a casing, of discharging mechanism, a trigger for controlling said discharging mechanism movable to cocked position, means for cock- 130

ing the gun and moving said trigger to cocked position, and means for preventing the accidental discharge of said discharging mechanism when said trigger is in cocked position including means upon said trigger cooperating with said casing.

8. In a gun, the combination with a casing, of a trigger mounted thereon and movable to cocked position, and means upon said trigger adapted to cooperate with said casing when said trigger is in cocked position for locking the same from accidental rotary movement.

9. In a gun, the combination with a casing having a chamber therewithin, of a plunger movable within said chamber, a trigger mounted upon said casing, means for cocking the gun and moving said trigger to cocked position, and means for locking said plunger from movement when the gun is cocked including a shoulder upon said trigger engageable with said casing, said shoulder being disengageable from said casing upon movement of said trigger.

10. In a gun, the combination with a casing having a chamber therewithin and a plunger movable within said chamber, of a trigger for controlling said plunger having a notch in its front face engageable in by a portion of said casing when said trigger is in cocked position, said plunger being dependent for its release upon movement of said trigger.

11. In a gun, the combination with a casing having a chamber therewithin and a plunger movable within said chamber, of a trigger member for controlling said plunger pivotally mounted upon said casing, and having provision for a bodily movement longitudinally of said casing, said trigger member having a notch in its front face engageable in by a portion of said casing when said trigger member is in cocked position, and means for yieldably moving said trigger member when in cocked position to bring its notch in engagement with a portion of said casing.

12. In a gun, the combination with a casing having a longitudinally extending chamber and a plunger movable within said chamber, trigger mechanism pivotally mounted upon said casing comprising a member having a latch for retaining said plunger in a predetermined position, said

member having a fixed axis of rotation, and a second member upon said trigger mechanism pivot and having provision for movement relative to said first-mentioned member longitudinally of said casing, said second-mentioned member having a shoulder engageable with said casing when said trigger mechanism is in cocked position, and means for rocking said first-mentioned member from said second-mentioned member.

13. In a gun, the combination with discharging mechanism, of a trigger having a rotary and a linear movement for controlling said discharging mechanism movable to cocked position, means for holding said discharging mechanism from discharge when said trigger is in cocked position, and means for locking said discharging mechanism from accidental discharge when said trigger is in cocked position, said locking means being dependent for its release upon movement of said trigger.

14. In a gun, the combination with a discharging mechanism, of a trigger having a rotary and a substantially linear movement for controlling said discharging mechanism movable to cocked position, and means for locking said trigger in cocked position against accidental rotary movement, said locking means being dependent for its release upon the substantially linear movement of said trigger.

15. In a gun, the combination with a casing, of discharging mechanism, a trigger having a rotary and a linear movement for controlling said discharging mechanism movable to cocked position, means for cocking the gun and moving said trigger to cocked position, and means for locking said discharging mechanism from accidental discharge when said trigger is in cocked position including means upon said trigger cooperating with said casing.

16. In a gun, the combination with discharging mechanism, of an adjustable trigger having a substantially linear and a rotary movement, said trigger controlling said discharging mechanism, and means for holding said trigger against rotary movement.

In testimony whereof I affix my signature.

ERNEST S. ROE.
